UNITED STATES PATENT OFFICE.

JOSEF YNGVE DAHLSTRAND, OF WELLSVILLE, NEW YORK.

ROTARY FLUID MOTOR.

Application filed August 29, 1923. Serial No. 659,936.

This invention relates in general to improvements in rotary fluid motors, and more particularly to steam turbines, and this invention, among other features, more especially aims to improve the casing structure, bearings, and the like of a steam turbine, with a view to increasing the efficiency and utility of the machine, together with reduction in cost of production and general improvement in design, whereby to facilitate the installation, operation and maintenance of such machines.

This invention, while particularly directed toward the improvement of the turbine casing, also involves an improved arrangement of the rotor, valves, and allied parts, and in the production involves a new and improved method of manufacturing the casing, whereby to reduce the cost of manufacture, insure accuracy in the parts, and increase the life of the machine.

Therefore, the principal objects and advantages of this invention reside in the provision of an improved steam turbine characterized by the embodiment therein of a novel casing, rotor and valve structures; the provision of an improved casing structure for steam and other fluid pressure operated motors; the provision of an improved casing structure for steam and other fluid pressure rotary prime movers, commonly known as turbines; the provision of a rotary fluid motor characterized by the provision of an improved combined casing and bearing structure; the provision of a rotary fluid motor or turbine characterized by the provision of an improved combined casing, steam inlet and exhaust structure, together with certain improvements in the bearing and valve structures; the provision of a rotary fluid motor or turbine characterized by the provision of an improved casing facilitating manufacture, assembly and installation, and improving the efficiency and utility of the machine, the provision of an improved method of producing the turbine casing and associated parts; and the provision of a turbine which is characterized by the embodiment therein of an improved governor valve and governor, together with certain improvements in the valve and governor, details to be more particularly pointed out as this description proceeds.

The foregoing and such further objects and advantages as may appear or be pointed out, are attained in the structural embodiment

ments of this invention, illustrated in the accompanying drawings, in which:

Figure 1 is a side elevational view of a turbine embodying the improvements of this invention.

Figure 2 is a vertical sectional view taken approximately on the longitudinal axis of Figure 1.

Figure 3 is a vertical sectional view taken on the line 3—3 of Figure 1, looking in the direction indicated by the arrows.

Figure 4 is an end elevational view taken from the right hand end of Figure 2.

Figure 5 is a top plan of the lower half 70 casing sections.

Figure 6 is a vertical longitudinal sectional view of another type of fluid motor or turbine embodying certain improvements.

Referring more particularly to the drawings, and first to Figures 1 to 4, inclusive, there is provided a multi-part casing 5, comprising in general the lower half which includes the steam end section 6 and exhaust end section 7; and the upper half 8 which is 80 placed upon the lower half when assembled. The sections 6 and 7 are designated as "steam end" and "exhaust end" sections for the reason that steam enters at the right end, as viewed in Figure 2, and exhausts at the 85 left end, through the sections mentioned. It will thus be observed that while three separate elements are employed in forming the casing, it is essentially constructed of two halves, the upper and lower, in which the 90 latter comprises two separable parts, or, as will later appear, may comprise three separable parts.

Referring first to the lower half of the casing, the steam end section 6 is provided 95 at its outer end with a base or foot portion 9, by which this end may be bolted to a floor or other support, and the inner end of said section is provided with a radial semi-annular flange 10. The steam end section is 100 furthermore provided with a substantially horizontal top flange 11, and a steam inlet duct or chamber 12, from the walls of which the foot portion or pedestal 9 extends; said flange conforming generally to the shape of 105 the section 6 in top plan.

The steam inlet duct 12 extends substantially in a semi-circle and is defined by the end wall of the section 6, partition 13, wall 14, and the top facing wall portions, 15 and 16, see Figure 5. The duct 12 therefore forms what is generally known as the "steam

ring", but, as will be observed, is confined within the steam end section of the lower half, and thereby eliminates all high pressure joints in the casing proper.

5 A steam inlet conduit 17 extends from the duct 12 and turns upwardly to afford an opening 18, bordered by the extended portion 19 of the flange 11, said extended portion being in a plane parallel to the axis of 10 the turbine, whereby the steam chest 20, may be bolted directly thereto and therefore assume a substantially vertical position. This arrangement facilitates installation, as it permits the steam line (not shown) to 15 come down straight from a steam header above the machine. Furthermore, the location of the steam inlet at the side rather than beneath the adjacent bearing permits of free circulation of air around the bearing, and prevents overheating of the bearing 20 due to proximity of the steam inlet.

It will be observed from viewing Figure 2 that an integral axial extension 21 extending from the steam inlet chamber or duct 12 is formed with the section 6 and serves as a 25 support for the adjacent bearing and container and governor to be later described.

The facing portions 15 and 16 also afford a firm foundation with the flange 11 for 30 reception and support of one portion of the upper section 8, as will appear.

The exhaust end section 7 includes a wall 22 which extends upwardly and toward the wall 14 of the section 6, the section 7 having 35 a substantially semi-annular radial flange 23, which is complementary to and abuts the flange 10, both of said flanges being bolted together as best seen in Figures 1 and 2. A flange 24, complementary to flange 11, forms 40 substantially a continuation of the latter when the sections 6 and 7 are joined.

The lower sections thus assembled receive the upper section 8, the latter having a generally semi-circular shape and being provided 45 with a continuous horizontal flange 25, which is perforated and conforms in shape to the flanges 11 and 24, said flange 25 abutting the flanges 11 and 24, and being bolted or otherwise fixedly secured thereto.

50 The upper ends of the walls 14 and 22 adjacent the shaft 26, are recessed at 27-27 to accommodate said shaft and the adjacent portions of the walls of the upper section 8 are similarly recessed at 28-28.

55 The exhaust end section 7 is provided with a relatively large expansion chamber 29 in communication with the exhaust duct 30, which latter is disposed in a substantially horizontal plane and is provided with the flange 31, for securing to an exhaust line, not shown.

60 A pedestal 32 forming an extension or continuation of the wall of the chamber 29 is cast integrally with the section 7 and its exhaust duct and said pedestal has feet por-

tions 33-33, perforated whereby they may be bolted to a floor or other support.

The shaft 26 is revolvable in bearings 34 and 35, the former being contained in a housing 36, mounted upon the extension 21, 70 and the latter being contained in a housing 37 mounted upon the upper face 38 of the pedestal 32.

As will be observed from an inspection of Figure 3, the extension 21 is substantially 75 semi-cylindrical and having an end flange 39 to which the complementary flange 40 on the lower half 41 of the bearing case 36 is fixedly attached, the upper half 42 of said bearing case being removably bolted or otherwise secured to the lower half. The bearing 34 is grasped and held, when the case 36 is assembled, by abutments 43 and 44 formed on the lower and upper halves, respectively. It will be observed that the bearing 34, is somewhat spheroidal in shape, that is, its abutment engaging faces are curved about a common center, and the abutment faces are similarly shaped, so that the bearing is centered, and as well prevented 85 against axial displacement. Rings 45 and 46 are secured adjustably to the shaft, and abut the opposite flat faces of the bearing, so that the shaft may be adjusted on its axis, and locked.

The other bearing 36 is mounted in its housing 37 on the shaft 26 similarly to the mounting of the bearing 34, with the exception that the adjusting rings, not being required there, are omitted.

It will be observed, therefore, that the bearings are both provided with supports directly beneath them or in the line of greatest pressure thereby always assuring the accurate alignment of the shaft, affording a 100 rigid support on the base of the machine, and thereby eliminating vibration to a large degree. At the same time this arrangement facilitates assembly or dismounting of the parts, and the shearing tendency on bolts where the bearings are supported by the casing direct is obviated entirely, that is, the flange 21 takes the weight of the shaft and rotor at the steam end, and the pedestal 32 takes the weight at the exhaust end.

105 At the points where the shaft 26 passes through the casing; that is, adjacent the recesses 27-27 and 28-28, there are provided packing rings, preferably of carbon and contained in packing cups 47 and 48, complementally bolted to the upper and lower casing sections.

110 A wheel or rotor 49 is fixed upon the shaft 26, within the casing 5, and comprises a disk portion having a relatively wide hub 50, and a relatively wide rim or peripheral flange 51, thereby accommodating two spaced peripheral rows of radial buckets or blades 52 and 53. This is especially advantageous 115 in that, first, a longer fit on the shaft is 120 in that, second, the buckets are more 125 advantageously located in the rim, and third, 130 the buckets are more advantageously 135

afforded, and secondly two series of blades are carried by the one wheel, thus preventing any misalignment of the blades of either series, which is entirely possible when the primary and secondary blades are carried on separate wheels. Furthermore, tortional stresses are thereby materially reduced.

The nozzle ring 54 is fixedly secured to the steam end section 6 in a groove 55 provided therefor, and thus cannot become accidentally displaced. The stationary row of buckets or blades 56 is affixed to an inwardly directed flange 57 (see Figure 2), and these blades lie between the rows 52 and 53 of rotor blades.

The steam chest 20, includes a housing 58, having an inlet 59 at its top and an outlet 60 at its bottom, said housing, at its medial portion, having an integral abutment portion 61 forming a valve chamber, and apertured to receive the valve seat bushing 62. An opening 63 is provided at one side of the steam chest, and a removable plate 64 closes said opening, a packing 65 being carried by the plate 64, for the valve stem 66.

The bushing 62 is provided with openings placing it in communication with the inlet and outlet and at its opposite ends said bushing has integrally formed valve seats 67 and 68. The bushing has one end 69 abutting a shoulder 70 on the abutment 61, and said bushing is fixedly maintained in position by the provision of bolts 71—71 which enter through the plate 64 and abut said bushing. Lock nuts 72 retain the bolts 71 against loosening.

The valve which here forms the governor valve of the machine, comprises a tubular body 73, having seat engaging peripheries 74 and 75 at its ends, the body being reinforced and guided by the provision of webs 76, and attached to the valve stem by the provision of an integral spider 77. It will be observed that the valve thus constructed will always evenly engage the valve seats, and as the valve seats are relatively immovable and the seat engaging portions of the valve similarly related, the expansion of the parts is substantially equal and no leakage can occur in the steam chest.

The valve 73 may be manually operated if desired, but usually is automatically actuated by the governor, which latter is mounted upon the shaft 26 within the housing 36 and is characterized especially by the provision of a construction which is substantially a unit, therefore facilitating complete attachment or removal of the governor without its disassembly.

As best seen in Figure 2, the governor comprises a housing 78, concentrically fixed to the adjacent end of the rotor shaft 26 within the bearing case 36, said housing 78 having a relatively long hub 79 affixed to the reduced portion 80 of the shaft 26, by the

provision of an abutting nut 81. The shaft 26 is further reduced and extends at 82 to support the governor sleeve 83. The sleeve 82 is non-slidably, but rotatively connected to the stationary spindle 84 by the provision of a union 85 containing a ball bearing 86, the spindle 84 extending through and sliding freely without contact in an opening 87 provided in a plug 88 which closes the outer end of the governor housing.

The inner end of the sleeve 83 is provided with a radial annular flange 89 abutting the inner end of a helical expansion spring 90, which latter has its opposite end abutting the plug 88, thus tending to restrain outward movement of the sleeve.

Two governor weights are provided designated 91 and 92 and these weights are retained by and having each a knife edge pivot engagement with an annulus 93 affixed to the hub 79 by a member 94. The inner ends of the weights are enlarged at 95 and engage the flange 89, so that as the weights are thrown outwardly the sleeve is moved outwardly against the tension of the spring 90.

The governor spindle, being non-rotatable, is connected by a pivot joint 96 to the lower end of a lever 97, fulcrumed at 98 in brackets 99 carried by the plate 64, the upper end of said lever being pivotally connected at 100 to the outer end of the valve stem 66.

It will be obvious that when the weights expand and force the sleeve 83 outward the spindle 84 will be similarly affected and through the lever 97 serve to close the valve 73 and reduce the speed.

The steam chest is also provided with an emergency governor valve 101, which is operated by a spring restrained pin 102, in the hub 79 of the governor. The valve 101 is preferably of the butterfly type mounted on a shaft 103 on which a lever 104 is fixedly mounted. The lever 104 is connected at one end to a helical spring 105 which tends to move the lever to close the valve, and said lever is constrained against such movement by a pawl member 106, which extends into the casing 36 to a point adjacent the pin 102, said pawl normally holding the lever in position to maintain the valve 101 open.

Should the governor valve fail to close or for any other reason the governor itself fail to accomplish its function, then the pin 102 moves to strike the pawl 106 and release the lever 104, permitting the butterfly valve to be closed by the spring and stopping the machine.

The improved method of manufacturing made possible by three part casing structure described involves the steps of taking two complemental half sections, for instance, two steam end sections, such as 6 and 7, and bolting them together, and then simultaneously facing and otherwise machining and boring these parts. Similarly, the other like sec-

tions, two at a time, are machined and bored, so that not only are the parts absolutely accurately made, but they are as well interchangeable. Furthermore, the rate of production is increased at least twenty-five percent over any of the usual methods of manufacture.

Another feature of the shape of the steam end section resides in the provision of the flange 11 as integral with the steam inlet, thereby affording the steam chest attachment flange 19 when facing the horizontal flange 11 of the casing.

In the alternative or modified construction shown in Figure 6, all the major features of the turbine of Figures 1 to 5, is adhered to, certain changes to be described, being made to produce what is commonly known as a two stage machine.

Referring to Figure 6, it will be observed that the steam end casing section 110 and exhaust end casing section 111, are identical with the sections 6 and 7, there, however, being provided two wheels 112 and 113, on the shaft 26^a, and thus necessitating the lengthening of the casing. This is accomplished by interposing the intermediate casing section 114 between the inner ends of the casing sections 110 and 111, each of said sections having abutting flanges 115, which are bolted or otherwise fixedly connected so as to form a lower half section of sufficient length to accommodate the two wheels and the primary and secondary nozzles and stationary blades.

In this arrangement, it will be noted that the primary nozzle ring 116 is carried by the section 110 and discharges steam into the two rows 117 of blades on the primary stage wheel 112, whence the steam passes to the first stage stationary blades 118 on the intermediate section 114. The section 114 carries a partition or vane 119 which is set into a machined groove therein. The partition 119 forms the lower half of a diaphragm arranged intermediate the primary and secondary stages of the turbine and contains the secondary series of nozzles 120, through which steam passes to the secondary or second stage blades 121 on the wheel 113, also passing the second stage stationary blades 122, which latter are mounted upon the exhaust section 111.

It is obviously necessary that the upper half 123 of the turbine casing be made larger than that of the construction of Figures 1 to 5, inclusive, and in order to isolate the wheels the vane 119 extends to and partly embraces the rotor shaft 26^a, as indicated at 124. The vane cooperates with the partition cast in the upper section 123, which partition forms the upper half of the diaphragm, to retain a bushing 126 surrounding said shaft. The partitions 119 and 125 and the bushing prevent passage of steam

from the first to the second stage chambers except through the nozzles 120.

It is noteworthy that the parts of the device of Figures 1 to 5 and Figure 6 are interchangeable. For instance, should the user have an installation including the device of Figures 1 to 5, and desire to increase the horsepower without installing an entirely new machine, the required parts, including the larger upper half, elongated shaft, additional wheel, and intermediate casing section and its vane 119 and blades 118 may be embodied without material alteration in the then existing installation.

It will be, therefore, appreciated that the parts of the machine are interchangeable and truly standardized, which is not only greatly desired by the purchasers, but also facilitates manufacture and reduces the cost of production by reducing the number of different parts required.

The casing construction, bearing supports and the basic idea of standardization is carried out in the larger machines of the condensing type, and therefore, while certain details have been emphasized, it will be understood that the right to make minor alterations is reserved within the scope of the claims.

I claim:

1. In a turbine, a casing comprising separable abutting bottom sections and a common top section, a shaft extending thru the casing, external bearings for the shaft, the bottom sections having steam inlet and exhaust chambers therein, the walls of said chambers being extended to form supporting pedestals for said bearings.

2. In a turbine, a casing comprising separable abutting sections, a shaft extending thru the casing, external bearings for the shaft, a steam inlet chamber in one of said sections arranged at one side of the adjacent bearing with an air space therebetween, an exhaust chamber in another of said sections, the walls of said chambers being continued and extended to support said bearings and to form pedestals for said casing.

3. In a turbine, a casing comprising separable abutting bottom sections and a spanning top section, a shaft extending thru the casing, external bearings for the shaft, a steam inlet chamber at one end of said casing and located in one of said sections to one side of the adjacent bearing, an exhaust chamber in another of said sections, the walls of said chambers being continued to form integral abutments for supporting said bearings.

4. In a turbine, a casing comprising separable abutting bottom sections and a spanning top section, a shaft extending thru the casing, external bearings for the shaft, a steam inlet chamber at one end of said casing and located in one of said sections to

one side of the adjacent bearing, an exhaust chamber in another of said sections, and abutments formed integral with the walls of said chambers and spaced from the casing sections for supporting said bearings.

5. In a turbine, the combination of separable abutting casing sections, one of said sections having a groove therein, a shaft, rotors on said shaft, spaced series of blades carried by the rotors, stationary blades carried by certain of the casing sections and arranged between said series of rotor blades, primary fluid nozzles mounted on one of the casing sections, a diaphragm fixedly mounted in said groove and secondary fluid nozzles in said diaphragm and located between said rotors.

6. In a turbine, a casing including two end and an intermediate coupling section, a shaft, a pair of rotors on said shaft, said rotors having each a pair of spaced series of blades, primary nozzles on one end section, stationary blades on said intermediate section, and a secondary series of nozzles on said intermediate section.

7. In a turbine, a casing including two end and an intermediate coupling section, a shaft, a pair of rotors on said shaft, said rotors having each a pair of spaced series of blades, primary nozzles on one end section, stationary blades on said intermediate section, a secondary series of nozzles on said intermediate section, and fixed blades on the other end section.

8. In a turbine, a casing including two end and an intermediate coupling section, a shaft, a pair of rotors on said shaft, said rotors having each a pair of spaced series of blades, primary nozzles on one end section, stationary blades on said intermediate section, arranged between the series of blades of one rotor, a secondary series of nozzles on said intermediate section, and a secondary series of fixed blades on the other end sections arranged between the series of blades of the other of said rotors.

9. In a turbine, a casing having a steam inlet chamber provided with an entrance arranged with its axis at right angles to the axis of the turbine and in a vertical plane.

10. In a turbine, in combination, a casing including an upper and a lower portion separably connected, the lower portion having an inlet chamber integral therewith formed with a horizontal flange arranged parallel to the axis of the turbine and affording a connecting support for a steam line.

11. In a turbine, in combination, a casing including an upper and a lower portion separably connected, the lower portion hav-

ing an inlet chamber integral therewith formed with a horizontal flange arranged parallel to the axis of the turbine and affording a connecting support for a steam chest. 65

12. In a turbine, in combination, a casing including an upper and a lower portion separably connected, the lower portion having an inlet chamber integral therewith formed with a horizontal flange in a plane 70 parallel to the axis of the turbine and a steam chest vertically arranged and connected to said horizontal flange.

13. In a turbine, in combination, a multi-part casing characterized by the provision 75 of a steam inlet chamber which is confined to one of the parts of the casing and terminates short of the junction of the casing parts whereby to eliminate high pressure fluid joints in said casing. 80

14. In a turbine, the combination of separable abutting bottom sections, a shaft, rotors on said shaft, spaced series of blades carried by said rotors, stationary blades carried by certain of the casing sections, a partition set in one of said casing sections, and a top section common to said bottom sections having a partition cast therein which cooperates with said first named partition to form a diaphragm arranged between said rotors. 90

15. In a turbine, the combination of separable abutting bottom sections, one of said sections having a groove therein, a shaft, rotors on said shaft, spaced series of blades carried by the rotors, 95 stationary blades carried by certain of the casing sections and arranged between said series of rotor blades, a partition fixed in said groove, and a top section common to said bottom sections having a partition cast 100 therein which cooperates with said first named partition to form a diaphragm arranged between said rotors.

16. In a turbine, the combination of separable abutting bottom sections, one of said sections having a groove therein, a shaft, rotors on said shaft, spaced series of blades carried by the rotors, stationary blades carried by certain of the casing sections and arranged between said series of rotor blades, 110 primary fluid nozzles mounted on one of the casing sections, a partition set in said groove and forming the lower half portion of a diaphragm adapted to be arranged between said rotors, secondary fluid nozzles in said partition, and a top section common to said bottom sections and having a partition cast 115 therein which cooperates with said first named partition to form the upper half of said diaphragm. 120

In testimony whereof I affix my signature.
JOSEF YNGVE DAHLSTRAND.
